UNITED STATES PATENT OFFICE

115,484

DESIGN FOR A WINDBREAKER JACKET

Robert L. Smith, Long Branch, N. J.

Application May 4, 1939, Serial No. 84,794

Term of patent 3½ years

To all whom it may concern:

Be it known that Robert L. Smith, a citizen of the United States and resident of Long Branch, in the county of Monmouth and State of New Jersey, has invented a new, original, and ornamental Design for a Windbreaker Jacket, of which the following is a specification, reference being had to the accompanying drawing, forming a part thereof.

Fig. 1 is a front elevational view of a windbreaker jacket, showing my new design.

Fig. 2 is a rear elevational view of the same.

I claim:

The ornamental design for a windbreaker jacket, as shown.

ROBERT L. SMITH.
